UNITED STATES PATENT OFFICE.

JOSEPH HILL, OF WILLIAMSPORT, PENNSYLVANIA.

STEAM-BOILER.

SPECIFICATION forming part of Letters Patent No. 268,673, dated December 5, 1882.

Application filed May 15, 1882. (No model.)

To all whom it may concern:

Be it known that I, JOSEPH HILL, of Williamsport, in the county of Lycoming and State of Pennsylvania, have invented a new and useful Improvement in Steam-Boilers; and I do hereby declare that the following is a full and exact description of the same, reference being had to the accompanying drawings, and to the letters of reference marked thereon.

10 The object of the invention which is herein-after described and illustrated is to so construct a steam-boiler that the products of combustion may be utilized for heating purposes by being brought in contact with and converted into inflammable gases by combination with the exhaust-steam, which, by suitable means, is re-introduced in a reheated condition into the boiler, thereby greatly lessening the amount of fuel, and consequently greatly reducing the 15 expense attending the employment of steam-boilers, as well as serving to increase the draft for supporting combustion.

To the accomplishment of the above the invention consists in the peculiar construction of 20 the boiler, whereby the products of combustion, in their passage through the flues of the boiler, are mixed and combined in the same flues with the exhaust-steam; and the invention further consists in the use of a cap or covering, which is secured to or constitutes the 25 rear end of the boiler, and is provided with a suitable space or chamber, into which the exhaust-steam pipe is tapped. This cap is also provided with a number of pipes or tubes, 30 which correspond to the flues of the boiler, opposite to or within the mouths of which they are arranged. These pipes communicate with the chamber or space above referred to, and through them the exhaust-steam is carried from 35 said chamber into the flues of the boiler, where it is brought in contact with the products of combustion, passing through the same toward the smoke-stack. As the flames from the fire-box strike directly upon the inner face of the 40 cap or covering and its tubes, the exhaust-steam, in passing therethrough, is reheated, and, being in this condition when brought in contact with the products of combustion, accomplishes effectively the object of the invention—viz., the utilization of the products of

combustion and the consequent saving of fuel, as well as the increase of draft.

For the better understanding of the invention, reference will frequently be made throughout the following description to the accompanying drawings, which form part of this specification, and in which—

Figure 1 is a sectional view of the boiler, and Fig. 2 a view in detail, showing the construction of the cap or covering for the rear end of said boiler.

Like letters refer to corresponding parts in both views.

In the drawings, A represents the boiler proper; B, the dome of said boiler, through which live steam passes to the engine or machinery to be operated, any suitable connection being made between said dome and engine. At the front end of the boiler is suitably located the smoke-stack C, which opens into a chamber or box, D, into which the products of combustion are discharged after passing through the flues of the boiler, the location of which flues will be hereinafter described. This box D may be provided with a removable or hinged covering to afford more ready access to the flues of the boiler for the purpose of cleaning them. The fire-box E has a proper grate, a, at its lower front portion, and in such portion the bottom of the fire-box has a suitable opening to permit the increase of the air and the escape of ashes. In the space formed above this fire-box E are placed a number of horizontal pipes, (marked b in the drawings,) said pipes forming the flues of the boiler and extending from the front to the rear thereof. At the front of the boiler they open into the box D, before mentioned, and at the rear end into a space formed between the end of said boiler and the inner surface of a cap or covering, F, which is secured to or constitutes an end of the boiler, and which is to be herein-after described. By this arrangement the products of combustion are carried from the fire-box E through the flues b and discharged into the box D, whence they escape through the smoke-stack C.

The construction of the cap F, before referred to, is clearly shown in Fig. 2 of the drawings. As shown in that figure, it is provided on each

side with projecting edges *c d d*, by means of which it may be conveniently secured in position, either permanently or in a removable way. To the inner surface of this cap are firmly secured, in any desirable manner, a number of pipes, *e*. These pipes *e* correspond in number to the flues *b*, before mentioned, and when the cap is in position on the boiler they occupy a position which will bring them directly opposite and in close proximity to said flues *b*, or within the mouths of said flues, in which case said pipes should be so much smaller than the said flues as will allow the passage of the products of combustion through said flues. If the cap *F* be of the form which is herein shown, it will be necessary to vary the length of these pipes *e* in order that their outer ends may be in the same plane. On the inside of this cap *F* is placed an extra or additional wall, *f*, to which are secured the pipes *e*, above mentioned, and between which and the outer wall or wall proper of said cap a space or chamber, *g*, is formed. Into this chamber the steam-exhaust pipe *h* enters, as also do the pipes *e*. Throughout the preceding reference has been made to a stationary boiler only. Should, however, it be desired to use the boiler on motors, it will be advantageous to provide it with an apron similar to one shown in dotted lines in Fig. 1. As shown in that figure, this apron is secured to the boiler at a point directly under the grate with which the fire-box *E* is provided. This apron serves to catch the air and to materially increase the draft on the fire.

Having thus described separately the different parts of the boiler, and having shown the position and use of each of said parts and their connection the one with the other, I will now describe the operation of the whole.

The fire being kindled in the fire-box *E*, the products of combustion are carried to the rear end of said fire-box, and thence into the flues *b* of the boiler, as indicated by arrows in Fig. 1.

The live steam thus generated is carried off through the dome *B* to the engine to be operated. The exhaust-steam is returned through the exhaust-pipe *h* to the chamber *g*, formed in the cap *F*. From this chamber, which is

thoroughly heated by reason of the direct impact of the flames against it, the exhaust-steam, which is reheated by its passage through said jacket, is carried through the pipes *e*, where it is still more heated, into the flues *b*, opposite to which the pipes *e* are located. Upon its entrance in this heated condition into these flues *b* the exhaust-steam mingles and combines with the products of combustion, forming inflammable gases of great heating-power, which burn in said flues, thereby saving fuel to a great extent. I do not assert any theory for this result, but am convinced by much experiment of the fact that there is a great increase of heat by means of the construction above described, and consequently a saving of fuel. From these flues these products of such combustion escape into the box *D*, into which the pipes *b* open, and thence to the open air through the smoke-stack *C*, having also materially increased the draft.

Having thus described my invention, what I claim as new therein, and that for which I desire to secure Letters Patent, is—

1. The combination, in a steam-boiler, of the cap *F*, composing the rear end of the same, against the inner wall of which the products of combustion strike on their way from the fire-box to the flues, said cap having a chamber provided with an inlet for exhaust-steam from the engine, and outlet-pipes terminating near the boiler-flues and the smoke-stack, all constructed and arranged so that all the steam from the cap *F* passes directly from such cap into the smoke-stack with the products of combustion; substantially as described.

2. In a steam-boiler, the combination of the steam cap *F*, provided with inlet and outlet pipes, the fire-box *E*, the ash-pit provided with the apron *i*, the flues *b*, and smoke-stack *C*, all arranged and operating substantially as described.

This specification signed and witnessed this 11th day of May, 1882.

JOSEPH HILL.
